GAME BOARD

Leonard A. Wilbur, Piedmont, Calif.

Application May 28, 1954, Serial No. 30,730

Term of patent 14 years

(Cl. D34—5)

To all whom it may concern:

Be it known that I, Leonard A. Wilbur, a citizen of the United States, residing at 50 Selborne Drive, Piedmont, State of California, have invented a new, original, and ornamental Design for a Game Board, of which the following is a specification, reference being had to the accompanying drawing, forming a part hereof.

Fig. 1 is a plan view of a game board showing my new design;

Fig. 2 is a side elevational view thereof.

I claim:

The ornamental design for a game board, as shown.
